UNITED STATES PATENT OFFICE.

ALBERT THALHEIMR, OF READING, PENNSYLVANIA.

APPARATUS FOR DRYING LUMBER.

SPECIFICATION forming part of Letters Patent No. 268,839, dated December 12, 1882.

Application filed July 22, 1882. (No model.)

To all whom it may concern:

Be it known that I, ALBERT THALHEIMR, of the city of Reading, county of Berks, State of Pennsylvania, have invented a new and useful Improvement in Apparatus for Lumber-Drying, of which the following is a specification.

The improvement relates more particularly to the drying of thin lumber or veneers and the means adopted to retain the same in a straight and unwarped condition.

Referring to the drawings herewith, forming a part of this specification, and in which similar parts are marked by letters of corresponding figures, Figure 1, Sheet 1, represents a side elevation of the housings, rolls, steam-pipes, and a partial view of the yoke for retaining the pipes in place. Fig. 2, Sheet 1, is a plan of the housings, rolls, foundation-plate, gearing, driving-shaft and pulley, steam-pipes, and yokes. Fig. 3, Sheet 2, represents a side elevation showing the actuating-gear. Fig. 4, Sheet 2, is a longitudinal sectional elevation of one of the upper rolls with gear attached and steam-pipe adjusted to blow steam in the same. Fig. 5, Sheet 2, is a longitudinal sectional elevation of one of the lower rolls, showing a gas-pipe and gas-burners arranged in the interior of the same, in all of which—

A represents the foundation-plate; B, the twin housings; C, the caps; D, the bearing-boxes for the lower rolls; E, the boxes for the upper rolls. F represents the rolls; G, the roll-heads; G', the necks or journals; G², stuffing-box glands; G³, waste-steam discharge; G⁴, scoop for discharging condensed water. H H are spur-gears on the outer necks of the rolls. J is a spur driving-pinion in gear with the wheels. J' is a shaft for the same, mounted in bearings J² in the housings. J³ is a band-pulley for giving motion to the gears and rolls. K K are steam or gas pipes. L is a yoke so arranged with relation to the steam and gas pipes that set-bolts L' L' shall retain the pipes in place within the necks of the rolls. M M are strong spiral or equivalent springs, placed upon the tops of the upper-roll bearing-boxes. M' are caps over the springs, and M² are housing-screws for compressing the springs by screwing down upon the caps M'. N represents brackets attached to the housing for the

purpose of carrying the gas-pipe, which passes from side to side through the rolls.

There has been considerable ingenuity displayed and large amounts of money spent in drying-kilns and presses for the purpose of drying, seasoning, and keeping straight and unwarped lumber taken directly from the saw or rafted in bulk—thus far, I believe, without positive and economical results.

My improvement offers a simple and inexpensive mode of securing the desired end, does away with extensive, costly, and dangerous dry-houses, reduces the capital necessarily locked up in great stocks of lumber, and insures the production of thin lumber that shall be level, straight, and out of wind.

The construction of the apparatus is as follows: Twin housings similar to the drawings are finished between the jambs to receive bearing-boxes D E; the lower boxes, D, being half-boxes, while the upper, E, are whole boxes. Both are bored to fit the journals or necks of the rolls F. The upper boxes, E, may be supported from or poised upon steelyards, as is common in rolling-mills, or they may rest upon lugs or pins in the housing-jambs, so arranged as to let the upper roll down within the minimum distance it is intended to come to the lower roll. The housings are preferably cast double, or twinned, as shown, as giving more stability to the apparatus. The foundations are cast either complete for each pair or lengthened out to receive as many couples as it is desired to use for the purpose of drying. The rolls are preferably built up, although they may be cast complete. I prefer to make them, as shown, with cast-iron heads and necks, and riveting to the same the shells forming the body of the roll. The shells may be of wrought-iron or copper. At one side of the housings, and on the projected necks of the upper rollers, I place suitable spur-gearing. Intermediate to the rolls, and above the line of their centers, so as to permit their adjustment, I place a spur-pinion and band-pulley shaft, having bearings in a box forming part of the twin housing, the pinion being in gear with the wheels on the roll-necks and the band-pulley suitably connected with a revolving shaft. On the side of the housing opposite to the gearing I have

the necks of the rolls counterbored to receive a stuffing-box gland, through which I pass a steam-delivery pipe, making the passage steam-tight by packing in the usual manner. This pipe may be connected with both sets of rolls, (top and bottom,) the connection with the main or boiler being at such distance from the center of the rolls as will admit of the necessary vertical movement of the top rolls without disturbing the connection. To give stability, I carry the main down to the floor, as shown, securing the end in a foot; and to prevent the steam (by reaction) driving the connection out of the roll-necks, I place a yoke over the center of the horizontal pipes, and by means of set-screws therein brought in contact with the elbow and to retain the same in place. The rolls, when steam-heated, have solid disk-heads, except when bored for ingress and egress of the steam, while the heads of the rolls which are gas-heated are provided with openings between the rim and journals for the admission of air to support the combustion of gas at the burners.

For moderately green lumber I use live steam in all of the rolls, and for very green I replace the steam with gas; or I may use a combination of both steam and gas to produce the desired result. For drying moderately green lumber, one set of housings and rolls running at a slow speed will be ample; and if it is desired to have the drying proceed more rapidly additional sets of the housings and rolls are put in the train. The lumber may then be passed through at a greater speed. In this way, having a sufficient number of rolls *en train*, the lumber may be received direct from the saw at the mill, and be delivered from the train perfectly seasoned and in a workman-like condition. The lumber while passing through the rolls has a certain compressive strain put upon it through the medium of the screws M^2 , and the steam passing into the rolls, or the gas burning therein, an intense drying-heat is obtained, which evaporates the watery particles exuded by the pressure, at same time thoroughly heating the lumber, which being firmly held while this process is being performed, it results in producing an unexceptionably fine-conditioned article of lumber.

I am well aware that hollow rolls, steam and gas heated, have been long known and used for drying of paper and in the manufacture of wadding, &c., and I do not therefore broadly claim the same; but I believe myself to be the first to use the same in the manner described for the purpose of preparing lumber, particu-

larly thin lumber and veneers, for immediate use in industrial operations.

Having shown the construction of my drying apparatus and described its application, I desire to secure by Letters Patent the following claims:

1. A lumber-drying apparatus composed of the following elements: foundation-plate A, 65 twin housings B, caps C, bearings D, E, and J^2 , hollow rolls F, provided with heads G, necks or journals G' , glands G^2 , waste-passages G^3 , discharge-scoop G^4 , spur-gears $H H$, pinion J, shaft J' , band-pulley J^3 , springs M, spring-caps M' , and housing-screws M^2 , steam and gas pipes K, yokes L, set-screws $L' L'$, and brackets N, all combined, arranged, and adapted to be operated in the manner and for the purpose set forth.

2. The twin housings B, provided with bearings D, E, and J^2 , with caps C, springs M, spring-caps M' , and housing-screws M^2 , in combination with hollow drying-rolls F, steam or gas pipes K, yokes L, gearing $H H$, J, pulley 80 J^3 , shaft J^2 , and foundation-plate A, substantially as and for the purpose specified.

3. The hollow rolls F, provided with imperforate disk-heads G, having counterbored or perforated necks G' , stuffing-box glands G^2 , 85 and gear-wheels $H H$, in combination with pinion J, shaft J' , pulley J^3 , twin housings B, bearings D E, steam-pipe K, yokes L, screws $L' L'$, and scoop G^4 , when arranged as shown and adapted to be used for the drying, compressing, and straightening of lumber, substantially as described, and for the purpose herein set forth.

4. The hollow rolls F, as described, provided with perforate disk-heads G, in combination 95 with twin housings B, bearings D, gas-pipe K, and the brackets N, adapted by the perforation of the gas-pipe within the rolls and the ignition of the gas to heat the upper portion of the shell of the roller in immediate contact 100 with the lumber passing through the rolls, whereby the drying process is hastened, as described, substantially as and for the purpose set forth.

5. The combination, in a roller or train drying apparatus, as described, of both steam and gas-flame heated rolls in pairs or as alternates, for the purpose set forth, and substantially as specified.

ALBERT THALHEIMR.
